A. M. KING

BOMB CASING

Filed Sept. 19, 1925

Fig. 2.

Inventor

Albert M. King

O'Neill - Brown

Attorneys

UNITED STATES PATENT OFFICE.

ALBERT M. KING, OF CASPER, WYOMING.

BOMB CASING.

Application filed September 19, 1925. Serial No. 57,452.

To all whom it may concern:

Be it known that I, ALBERT M. KING, a citizen of the United States, and resident of Casper, in the county of Natrona and State 5 of Wyoming, have invented certain new and useful Improvements in Bomb Casings; and I do hereby declare the following to be a full, clear, and exact description of the invention, such as will enable others skilled in 10 the art to which it appertains to make and use the same.

This invention relates to bombs for use in shooting oil wells, and more specifically to a bomb casing provided with a metallic compartment adapted for the reception of the explosive charge, and another compartment adapted for the reception of time-controlled mechanism which governs the time of explosion of said charge.

It is broadly old in the art to provide time-controlled mechanisms to electrically ignite the charge carried by a bomb, but there is grave danger in the employment of such a device, due to the fact that, when such mechanism is actuated, the explosion is instantaneous. In the oil fields many fatalities have occurred because of careless manipulation of such bombs, while setting the timing mechanisms, or in accidentally dropping the bomb while the mechanism is set to safety position.

In my companion application Ser. No. 57,451 filed of even date therewith, I disclose a mechanism in which is provided a chain of instrumentalities adapted to explode the charge, said chain including an element, such as a slow fuse which, after the timing mechanism has been actuated, delays the explosion for a considerable time. 40 In the use of this device the accidental activation of the timing mechanism will not result in the explosion until after the operator has had an opportunity of disrupting the chain leading to the charge, or has at 45 least been given the opportunity to reach a point of safety.

The primary object of the instant invention is the provision of means properly housing the timing mechanism and at the same time permitting visual inspection thereof by the operator so that he may be instantly advised when the said mechanism is inadvertently actuated to light the fuse.

Another object of the invention is the provision of a water-proof housing for such timing mechanism, which housing is of a

material which is not only transparent, so as to permit a view of said mechanism at all times, but which, in the event of inadvertent actuation of the said mechanism, may also 60 be easily broken to give ready access to the fuse so that the latter may be quickly ruptured whereby to destroy the chain of instrumentalities leading to the explosion of 65 the charge.

Other objects of the invention will be made apparent in the following specifications, when taken in connection with the drawings forming a part thereof.

In said drawings;

Fig. 1 is a vertical section taken through a bomb equipped with my invention, and,

Fig. 2 is a transverse section of said bomb, on the line 2—2 of Fig. 1.

Now referring specifically to the drawings, 75 Fig. 1 indicates a metallic casing containing the explosive charge 2. A slow-fuse 3, leads into the chamber 1, and carries a percussion cap 4 at its end, in proximity to the dynamite 2, or other explosive constituting the 80 charge.

The chamber 1 is somewhat enlarged at its upper periphery, and is provided with an annular groove 5, concentric with the opening in the chamber. A cylinder 6, of 85 glass or other transparent frangible material, is formed so that its lower periphery fits snugly into the groove 5, a lead packing being preferably positioned below the end of the cylinder 6 to effect a water-tight joint. 90 A cap 7 is provided for the upper end of said cylinder 6, a groove 8 being cut into the lower surface of said cap and adapted to also receive a lead packing and the upper periphery of the cylinder 6, as will be understood.

The upper surface of the enlarged portion of the casing is provided with a plurality of screw-threaded sockets, adapted to receive tie-bolts 9 which extend through 100 apertures in the cap 7 and into said sockets, both ends of said bolts being screw-threaded. After the bolts are screwed into said sockets, and the cap 7 so applied that the apertures therein embrace the bolts 9, locking nuts 9' 105 are applied to the ends of the bolts and tightly screwed down onto the cap 7, compressing the lead packings in the grooves in the cap and casing and thereby effecting water-tight joints, and also firmly securing 110 the cylinder 6 in position.

The timing mechanism controls a chain

2
of instrumentalities which operates to explode the charge, consisting of one or more fulminates carried by the upper portion of the fuse, and which are exploded by the 5 timing mechanism to ignite the fuse; the fuse itself, and the percussion cap 4 which explodes to set off the charge 2.

As clearly and specifically set forth in my companion application heretofore referred 10 to, the timing mechanism consists of a time-piece 10, to the outside of which is secured a semi-cylindrical shell 11. A shelf 12 extends across the shell 11, as does also a support 13, and a spring-actuated swinging arm 15 10' is pivotally mounted on a fixed pin 14 extending between the shelf 12 and the support 13. The fuse 3 carries one or more fulminates at its upper end, which end is held by the shell 11 so as to present the ful- 20 minate for contact by the head 15 of the swinging arm 10'. A detent 16 is adapted to restrain the swinging arm 10' in "set" position, and the alarm shaft 17 of the time-piece carries a blade 18 which is provided 25 with a vertically-extending slot adapted to receive the extreme end 19 of the detent, and to prevent movement of the latter to releasing position while the alarm shaft is fixed in one position. The blade 18 also 30 carries a cam 20 at its lower edge, which cam, during normal rotation of the shaft 17, while the alarm is being sounded, contacts the detent 16 and moves it to releasing position, thereby allowing the spring-actuated 35 head 15 to contact the fulminate on the fuse, and set into operation the chain of instru- mentality leading to the explosion of the charge.

It is to be noted that the outer periphery 40 of the shell 11 makes a neat fit with the inner surface of the cylinder 6. In actual practice the clock controls are all set to cause ignition of the fuse at a predetermined time, the end 19 of the detent 16 resting in 45 the slot in the blade 18, whereby the ignition mechanism is at "safety." The device is then assembled as indicated in Fig. 1, the cap 4 being first lowered into the chamber containing the explosive charge, as great a 50 length of the fuse 3 as desired being provided beneath the clock-piece 10 and the explosive. The timing mechanism is pushed downwardly within the cylinder until the lower edge of the clock 10 contacts the inner 55 periphery of the casing 1, and the cap 7 is then applied in position as above set forth. Before the cap 7 is applied, in case of inadvertent actuation of the timing mechanism resulting in ignition of the fuse 3, 60 the whole device, including the cylinder 6, may be moved from the proximity of the chamber 1, and the fuse 3 disrupted. After the cap 7 is applied the operator may at all times view the mechanism and fuse through

the transparent cylinder 6, and, in case of inadvertent actuation of the igniter, may break the glass cylinder 6 and withdraw or disrupt the fuse long before the percussion cap 4 is exploded.

The device is provided with a bail 21 for 70 convenience in handling after assembly.

From the foregoing it will be noted that the utilization of the device described greatly minimizes the danger heretofore incident to the handling of bombs of this character, 75 since the transparent casing not only permits the operator at all times to satisfy himself that the fuse is not lighted, but also affords him ready opportunity to disrupt the latter long before the dangerous explo- 80 sion can take place.

Various modifications of the structure herein depicted may be suggested to those skilled in the art. For instance instead of a cylinder 6 made entirely of transparent material a frangible transparent window might be provided in the casing for the timing mechanism, or a transparent window which could be opened to permit access to the fuse. Such structures fall within the 85 province of my invention, as do all other embodiments falling fairly within the scope 90 of the appended claims.

What I claim is:

1. A housing for bombs and igniters, comprising a metallic casing for the explosive charge, and a transparent casing for the igniter. 95

2. A housing for bombs and igniters, comprising a metallic housing for the explosive charge, and a frangible transparent casing for the igniter. 100

3. A composite casing for bombs of the class including an explosive charge and an automatic igniter, comprising a metallic casing for the charge, and a transparent casing for the igniter, and means for securing said transparent casing to said metallic casing. 105

4. A composite casing for bombs of the class including an explosive charge, an automatic igniter, and a slow-fuse leading from the igniter to the charge, comprising a metallic casing for the charge, and a casing for the igniter, said latter casing at all times permitting a view of the igniter and of the 110 fuse leading to the charge. 115

5. A composite casing for bombs of the class including an explosive charge and an automatic igniter operatively connected to the charge, comprising a metallic casing for the explosive charge, a transparent, frangible casing for the igniter, and means for securing said casings together to form a water-tight compartment. 120

In testimony whereof I affix my signature. 125

ALBERT M. KING.
